UNITED STATES PATENT OFFICE

JAMES A. PAISLEY, OF CLEVELAND, OHIO

APPARATUS FOR LOADING MINE CARS

Application filed February 2, 1929. Serial No. 336,961.

This invention relates to apparatus for loading mine cars, and more particularly to an improved form of plow for use in an apparatus such as disclosed in my prior application Serial Number 320,097, filed November 17, 1928, of which apparatus the present invention constitutes an improvement.

As shown and described in my prior application, the apparatus comprises a conveyor 10 of the endless type which is located over the pit car tracks and in position to receive the coal from a pit car loader of any approved form which will deliver the coal from a lower level to a higher level and deposit the same upon the receiving end of the loading conveyor. Such loading conveyor, in the construction illustrated, is provided with a plow which rests thereupon and is capable of being moved along the conveyor by the operator, by manual power applied at will, as through flexible lines which enable the operator to move the plow along the conveyor so that it may be positioned over the several cars successively, in the train, the plow causing the coal as it is carried along the conveyor to be diverted laterally off of the conveyor onto the underlying car which is being loaded. The manual control of the plow through the flexible cables and lines, or other approved 20 instrumentalities, enables the operator to exercise his judgment as to the time when the plow is moved along the conveyor, from one car to be loaded, to and over an adjacent car. The operator is also enabled to control the speed of movement of the plow over the conveyor to control the distribution of the coal in the cars being loaded, which enables the loading operation of the successive cars to be performed with great efficiency and dispatch.

The present invention seeks to improve the plow structure used in the apparatus by the provision of a movable apron at the forward end of the plow which is flexibly connected with a portion of the plow, and is adapted to rest upon the surface of the conveyor belt so that it will follow the irregularities thereof, and not wear or dig into the fasteners of the belt. By riding evenly over the belt, because of its hinged connection with the plow, the apron insures engagement of all of the coal

which is being conveyed towards the plow, with the plow, and prevents the smaller sizes of the coal from working under the plow, this objectionable condition often resulting in causing the plow to be raised from the conveyor. The plow rests upon a platform which forms a base for the plow, and to which base the apron is flexibly connected, whereby the weight of the coal upon the platform holds the apron in close engagement with the conveyor, thus preventing the objectionable condition above referred to.

The foregoing, and other important and valuable features of the invention will be apparent from the following description when considered in connection with the accompanying drawings, and the novel elements will be pointed out in the appended claims.

In the drawings:

Fig. 1 is a view in side elevation, partly broken away, showing the apparatus for loading cars, with the novel features hereof;

Fig. 2 is a plan view thereof;

Fig. 3 is a plan view of a portion of the conveyor with the plow supported thereover;

Fig. 4 is a view in side elevation thereof;

Fig. 5 is a sectional view on line 5—5, Fig. 3, and

Fig. 6 is a sectional view on line 6—6, Fig. 3, looking in the direction of the arrows.

Referring to Figs. 1 and 2 of the drawings, a face conveyor, such as 4, is located in position to carry the coal to and deposit it upon the receiving end of a pit car loader 6, which is herein shown as of the endless type and whose frame may be supported for movement upon a track 10 by wheels 8, such parts as so far described being usual and well known in mine car loading practice where coal is conveyed from a pit car loader to the cars which are brought beneath the discharge end, as 12, of the pit car loader 6, and as each car is loaded it is withdrawn from position beneath the pit car loader, and an empty car is pushed up the track into position for loading.

As set forth in my co-pending application above referred to, I provide a conveyor, as 14, whose entering end portion 16 is located below the discharge end 12 of the pit car

loader 6, the conveyor 14 being of the endless belt type, and being located horizontally above the tracks 10 on which mine cars, herein indicated by the numerals 18, 19, 20 and 21 move as they are brought into loading position, and are carried out of such position by the locomotive.

As herein shown, the frame of the conveyor 14 is provided at its upper edges with longitudinally arranged channel irons 16 between which, and lying flat upon the conveyor frame, lies the upper run of the flexible belt 24. The plow 30, which is herein shown as provided with two inclined sides converging to an edge, is mounted upon a platform 31, which rests upon channel irons 32 so as to be elevated above the belt 24, the platform being supported at its forward and rear edges upon bars 28, 29, respectively. An apron 25 is hingedly connected, as shown at 26, to one of the supporting bars 28 for the platform 31 of the plow. This apron may be made of sheet metal of suitable gauge, and its sides 23 are turned down to close the openings which would otherwise be present at the ends of the apron, and into which coal might, and probably would be forced by the conveyor. By reason of the fact that the apron 25 is hingedly connected to the plow, said apron will be caused to rest at all times upon the conveyor belt, its flexible connection with the plow causing the apron to follow irregularities and inequalities of the belt as the plow and apron are moved relatively to said belt.

The sides of the frame of the plow are preferably provided with eyes 21, or other equivalent means for the attachment thereto of the ends of flexible lines or cables 33. These cables are attached at one end to the eyes 21, and as to the cable on one side of the plow, the same is herein shown as passed over an idler 24, which is carried by a bracket projecting from one side of the conveyor frame 14, the free end of the cable being thence led across conveniently to a cleat as 40, on the other side of the conveyor frame, to which said cable end is secured. The other cable 33 may be led directly rearwardly along the conveyor frame and fastened to another cleat 40, as herein shown.

It will be seen from the construction as described that in the operation of loading the cars 18, 19, 20 and 21, the coal is conveyed by the pit car loader 6 and deposited upon the conveyor belt 24, and carried by said belt along and over the several cars located below the conveyor. The plow 30 which rests freely upon the conveyor frame, is capable of such movement along the frame and over the conveyor belt, by manipulation of the flexible connections 33, 33, as to be controllably moved by the operator in position, first over the car 18, and thereafter over the cars 19, 20 and 21, in succession, to cause the

coal to be deflected laterally from the conveyor, and loaded successively onto the several cars according to the location of the plow.

In the operation of loading cars it will be evident that the operator will first start with the plow over the car 18, and as the coal is carried by the conveyor to the plow, the latter will intercept the coal and deflect it laterally, so that the coal will fall off of the conveyor belt at the two sides of said belt, and by movement of the plow forward will be gradually caused to pile up in the car, the distribution of the coal during the loading operation being controllable by the operator in the movement of the plow. This operation will be repeated successively over the remaining cars as 19, 20 and 21 until the last car in the train has been loaded. During the loading operation the apron 5 will rest lightly upon the belt of the conveyor and will cause all of the coal including the smaller particles thereof to be picked up and caused to travel along the apron and the forward portion of the platform 31 to the plow 30, the flexible connection of the apron with the plow permitting the apron to lie closely to the surface of the belt, so that none of the coal will be carried under the plow so as to interfere with its free movements or cause wedging of the coal between the belt and plow. The weight of the coal that lies on the plow frame or platform has been found in practice to hold the plow on the conveyor. The large lumps of coal or other material being conveyed are cushioned by the fine coal that builds up on the plow, thereby preventing such large lumps from striking the plow a heavy blow to injure or displace the same.

It is to be understood that changes may be made in the particular arrangement of the elements shown, or in their specific construction, without departing from the spirit of the invention provided such variations in arrangement or structure are within the scope of the following claims.

I claim:

1. In an apparatus of the class described, the combination with a conveyor for granular material, of a plow movable over said conveyor, said plow having at its leading end an apron movably connected therewith and adapted to extend to the surface of and rest upon said conveyor.

2. An apparatus of the class described comprising a conveyor for granular material, a plow located over and movable along said conveyor and having a platform, and a movable apron pivotally connected with said platform and arranged to extend therefrom to the surface of the conveyor.

3. In an apparatus of the class described, the combination with a conveyor for granular material, of a plow movable thereover, a platform supporting said plow, and an

apron flexibly connected with the leading end of said platform and adapted at its forward end to rest upon said conveyor.

4. In an apparatus of the class described, the combination with a conveyor for granular material, of a plow comprising a platform elevated above said conveyor, and deflecting blades mounted upon said platform, of an apron having its rear end portion flexibly connected with said platform for free movements relative thereto in a direction transversely of the plane of said conveyor, the forward end of said apron being adapted to rest upon the surface of the conveyor.

5. In an apparatus for loading cars with granular material, a belt conveyor arranged to overlie a plurality of cars, and a plow mounted above said conveyor and movable thereover, of an apron flexibly connected with said plow and arranged to rest at its forward end upon said conveyor, said apron comprising a bottom portion and enclosing sides.

6. In an apparatus of the class described, a plow arranged for movements along a horizontally disposed conveyor, said plow comprising a platform, means for supporting said platform a distance above the surface of the conveyor, deflecting blades mounted upon said platform, and an apron flexibly connected with the forward portion of said platform and arranged to normally lie at an inclination thereto and with its forward edge in free engagement with said conveyor.

7. In an apparatus of the class described, the combination with a flexible, longitudinally movable conveyor for granular material, of a plow mounted for movements above said conveyor and longitudinally thereof, said plow comprising an elevated platform, angularly arranged deflecting blades supported upon said platform so as to leave a receiving space at the leading end of said blades, and an apron having its rear end portion hinged to the forward portion of said platform and its leading end normally adapted to rest upon the surface of the conveyor, whereby the hinge connection between the apron and conveyor platform permits the leading end of said apron to rise and fall in following the inequalities or irregularities of the conveyor during the movement thereof.

8. In an apparatus of the class described, the combination with a flexible conveyor for granular material, of a plow mounted upon and free to move longitudinally of said conveyor, means whereby said plow may be manually moved in a longitudinal direction over said conveyor at the will of an operator, and an apron flexibly connected with the forward portion of said plow and arranged to engage said conveyor at its leading end and to maintain engagement with said conveyor as said plow is being moved thereover.

9. In an apparatus of the class described,

the combination with a conveyor of the belt type for granular material, of a plow movable over said conveyor and provided with a supporting platform, an apron flexibly connected to the forward portion of said platform, said platform extending beyond the shares of the plow and said apron being freely hinged thereto and adapted to rest upon and ride over the conveyor, whereby the granular material will be caused by the relative movement of the plow and conveyor to accumulate on said platform and by its weight hold the device down upon the conveyor.

In testimony whereof I have hereunto set my hand this 31st day of January, A. D. 1929.

JAMES A. PAISLEY.
